FOREIGN PATENT DOCUMENTS

GB 2454949 A * 5/2009

Primary Examiner — Sheryl Lane*Assistant Examiner* — Calvin E Vansant(74) *Attorney, Agent, or Firm* — Taft Stettinius & Hollister LLP(57) **CLAIM**

The ornamental design for a watch dial, as shown and described.

DESCRIPTION

FIG. 1 is a front elevational view of a watch dial showing my new design;

FIG. 2 is a side view thereof; and,

FIG. 3 is a front perspective view thereof.

The claimed design includes arc-shaped two-dimensional features printed on a planar front surface of the watch dial to provide an ornamental pattern.
